UNITED STATES PATENT OFFICE.

ROBERT T. POLLOCK, OF BOSTON, MASSACHUSETTS, ASSIGNOR TO UNIVERSAL OIL PRODUCTS COMPANY, OF CHICAGO, ILLINOIS, A CORPORATION OF SOUTH DAKOTA.

PROCESS FOR CONVERTING HYDROCARBONS.

Application filed November 25, 1919. Serial No. 339,782.

This invention relates to improvements in process and apparatus for converting hydrocarbons and refers more particularly to a process and apparatus in which relatively heavy hydrocarbons such as gas oil cut from crude petroleum, having no material percentage of gasoline, has a substantial portion of its content converted into gasoline or similar low boiling point hydrocarbons.

10 Among the salient objects of the invention are to provide a continuous process in which the oil to be treated is fed continuously to a cracking zone (preferably first passing through and being preheated by the outgoing vapors) and is then vaporized; to provide a process in which certain of the vapors, to wit, the heavier ones, are subjected to a reflux condensing action and are then preferably continuously returned to the body of fresh incoming charging stock in regulated quantities; to provide a process in which the oil and vapors are maintained under a regulated vapor pressure; both during distillation and condensation, and in which gasoline of a substantially given end point or boiling point may be produced; to provide certain improvements in simplification and efficiency of operation, and in general 20 to provide an improved process of the character described.

To more clearly understand the invention, I have shown in the accompanying drawing a somewhat diagrammatic view, illustrating 35 the apparatus.

Describing this drawing in detail, 1 designates the furnace in which is mounted a coil 2, which serves as the cracking zone. Above the coil 2 is positioned a vapor chamber or 40 expansion chamber 3, which is connected to the coil by the pipe 4. The vapors pass from the upper end of the chamber 3 to a riser or vapor line 5 in which is positioned a valve 6. The vapor chamber is also provided with a residuum drawoff 7, provided with a throttle valve 8.

The delivery end of the vapor line 5 is connected to the lower portion of a reflux condenser or dephlegmator 9. This dephlegmator is provided with a series of baffles 10 of any desired form or construction. The uncondensed vapors pass from the upper end of the dephlegmator through pipe 11 into a water condenser 12. This water condenser 12 is preferably similar to a vertical

tube boiler, the construction being generally shown in the drawing and the water passing through the tubes and the oil vapors around the tubes. The condensed vapors pass from the lower end of the condenser 12 to a receiving tank 13, which tank is provided with liquid drawoff 14, controlled by valve 15 and gas outlet 16, controlled by valve 17. Pressure valve 18 is also provided.

Describing now the manner in which the 65 fresh raw charging stock is fed to the apparatus, it is drawn from any suitable source of supply through pipe 19 by means of pump 20. The pump delivers it under pressure to line 21 which leads upwardly to the 70 upper end of the dephlegmator 9, as shown at 22. A throttle valve 23 is interposed in the line 21. The oil which passes into the dephlegmator is, of course, preheated by the rising vapors and in turn tends to further assist the reflux condensing action.

If desired, however, the raw oil may itself be preheated before it reaches the charging pump 20. The fresh oil and the reflux condensate will pass to a reduced extension 24 80 connected to the lower end of the dephlegmator 9. From this by line 25 the charging stock and reflux condensate reaches the inlet of the cracking coil 2. Any excess of a mixture of raw oil and condensate will 85 pass through line 26 into the tank 27. This tank 27 is provided at its lower end with a drawoff line 28 controlled by valve 29, leading to any suitable receiving tank. The valve 29 is in the preferable operation, 90 closed.

A second line 30 leads from the tank 27 to a second pump 31. This line 30 is also provided with a control valve 32. The pump 31 is connected by branch pipe 33 to the 95 charging line 21. This charging line 21 is provided at its lower end with an extension 34, which is secured to the line 30 and is provided with a control valve 35.

The arrangement is such that by regulating the valve 35, the amount of a mixture of raw oil and condensate pumped into the line 21 can be controlled. In other words, to the extent that the valve 35 is open, the oil coming from the line 30 will circulate from 30 100 through the pump 31, line 33 and back through valve 35 to line 30 or rise through pipe 21 and return to the dephlegmator.

The following illustrative run may be given: Gas oil from say, the Kansas field, 110

of 32° B. may be delivered to the charging pump and thence by line 21 to the dephlegmator in the manner heretofore described. The oil, as it passes through the cracking tubes 2 is heated to an oil temperature of 750° F. and maintained under a pressure 130 lbs. This pressure is maintained throughout the system by suitably controlling the various outlet valves in the drawing off lines. From 30% to 40% of this gas oil may be thus converted into substantially 400 end point gasoline of say, 56 to 58 B. gravity.

It is to be noted that the regulated quantities of oil which are subjected to the dephlegmator are constantly being returned to the charging line for proper treatment. Also that they may or may not again pass through the dephlegmator, depending upon the manner in which the valves are regulated. For example, the fresh oil may all pass up through the line 21 but none of it may cut back to either pump, by tightly closing the valves 32, 35 and 39 and shutting off the pump 31.

I claim as my invention:

1. A dephlegmating process for separating insufficiently cracked vapors from the sufficiently cracked vapors while said vapors are passing through a dephlegmator, which comprises continuously circulating a cooling medium in a closed ring, a portion of which ring includes the dephlegmator where the cooling medium is in heat interchanging relationship with the vapors, in removing a portion of the medium from the ring, and in replacing the removed portion with fresh cooling medium from a source extraneous of the ring.
2. A dephlegmating process for separating insufficiently from sufficiently cracked vapors, which comprises passing the vapors

through a dephlegmator, in continuously circulating a cooling medium moving in a stream in a closed ring, a portion of which ring includes the dephlegmator where the cooling medium is brought in heat interchanging relationship with the vapors, in removing a portion of the cooling medium from the ring, and in replacing the removed portion with fresh cooling medium introduced to the ring from a source extraneous of the ring.

3. In a process for dephlegmating oil vapors wherein the vapors are introduced to a dephlegmator having a vapor inlet and a vapor outlet, in which dephlegmator the cracked vapors are separated from the insufficiently cracked vapors, the steps consisting in continuously circulating a cooling liquid in a closed ring, a portion of which ring includes the dephlegmator, where the cooling liquid is in heat interchange relationship with the vapors, and in removing a portion of the liquid from the ring, and replacing the removed portion with fresh cooling liquid from a source extraneous of the ring.

4. In a process for dephlegmating vapors wherein oil vapors are introduced to a dephlegmator having a vapor inlet and a vapor outlet, in which dephlegmator cracked vapors are separated from the insufficiently cracked vapors, the process consisting in continuously circulating a cooling medium of oil in a closed ring, a portion of which ring includes the dephlegmator where the vapors are brought in heat interchanging relationship with the cooling medium, in removing a portion of oil from the ring, and in continuously replacing the removed portion with fresh cooling medium from a source extraneous of the ring.

ROBERT T. POLLOCK.
